Primary Examiner — Marie D. Fast Horse(74) *Attorney, Agent, or Firm* — Buchanan Ingersoll & Rooney PC(57) **CLAIM**

The ornamental design for a point-of-sale terminal, as shown and described.

DESCRIPTION

FIG. 1 is a reduced-scale front, right side, top perspective view of a point-of-sale terminal showing our new design; FIG. 2 is a front elevational view thereof; FIG. 3 is a rear elevational view thereof; FIG. 4 is a left side view thereof; FIG. 5 is a right side view thereof; FIG. 6 is a top plan view thereof; FIG. 7 is a bottom plan view thereof; and, FIG. 8 is a reduced-scale perspective view thereof, shown in an alternate state with an additional environmental customer display.

(Continued)

The broken lines depict environmental structure that form no part of the claimed design.
